UNITED STATES PATENT OFFICE.

EDWARD R. VIVES, OF NEW YORK, N. Y., ASSIGNOR TO VESDAL CREATIONS, INC., OF NEW YORK, N. Y., A CORPORATION OF NEW YORK.

LOCK.

Application filed March 17, 1923. Serial No. 625,817.

To all whom it may concern:

Be it known that I, EDWARD R. VIVES, a subject of the King of Spain, residing at New York, in the county of New York and State of New York, have invented certain new and useful Improvements in Locks, of which the following is a specification, reference being had therein to the accompanying drawing.

10 The present invention relates to combination locks of the multiple key type.

The object of this invention is, in general to produce a combination lock of the kind mentioned which is of simple and rugged construction and yet practically impossible of operation except by one provided with a key corresponding to the particular combination for which the lock has been set. The invention is also designed to produce a lock in which the number of possible combinations is practically unlimited and in which the combination can be changed quickly and easily. A further object of this invention is to produce a lock which is adapted for operation by a key of simple and cheap construction which can be readily formed by any one who has knowledge of the combination. Other objects and advantages of the invention will become apparent 30 hereinafter.

Referring to the accompanying drawings for a particular description of one embodiment of this invention:

Fig. 1 is an inside elevation of a door closure provided with a lock constructed in accordance with the present invention.

Fig. 2 is a horizontal section through 2-2 of Fig. 1.

Fig. 3 is a central vertical section of Fig. 2. 40 Fig. 4 is a vertical sectional view of the key-operated bolt controlling mechanism taken on line 4-4 of Fig. 2.

Fig. 5 is a view similar to Fig. 4, showing a key inserted.

45 Fig. 6 is an outside face view of the member shown by Figs. 4 and 5.

Fig. 7 is a side elevation of a master key adapted for use with a lock constructed according to the present invention.

50 Fig. 8 is a longitudinal sectional view of the key shown by Fig. 7.

Fig. 9 is a perspective view of a key blank.

Fig. 10 is a perspective view of a key of another construction.

55 The lock is shown in Fig. 1 applied to an

ordinary door. The bolt 10 and its operating mechanism are mounted in a casing 11 secured in a recess of the door 12 and provided with a cover plate having an opening through which the bolt is adapted to be projected and retracted, as usual. Secured to, or formed with, the body of bolt 10 is an open rectangular extension 13, the rear end of which is spaced from the rear wall of casing 11. Any suitable form of spring may be provided for projecting the bolt. The drawings illustrate for this purpose elliptic springs 14 and 15 bearing against the rear end of bolt extension 13 and the rear wall of casing 11, respectively. The means illustrated to retract the bolt, after the proper key has been inserted, consists of a cam arm 16 bearing against the inner wall of bolt extension 13 and secured to a transverse shaft 17, which projects on the outer side of the door and is provided with a suitable knob or handle. (Not shown.)

The bolt controlling mechanism comprises a flat rectangular member 18 which extends through the door and through the casing 11 at right angles to said casing and bolt. As clearly shown in Fig. 2, the member 18 has parallel side portions extending through casing 11 and through registering slots in said casing and door respectively. The member 18 has a thickened portion forming shoulders which engage the outer side of casing 11 and a still thicker portion which projects on the outside of the door and forms shoulders engaging the outer face of the door. The said member 18, therefore, is adapted to be withdrawn from the casing and door from the outside after suitable fastening means operable only from the inside have been removed. Formed in member 18 are a plurality of superposed parallel channels 19, which have reduced key-receiving openings 20 and which incline upwardly from said openings extending completely through member 18. A removable closure 100 for the unreduced openings of channels 19 may be provided by a slidible plate 21 which fits over the end of member 18 and has re-entrant flanges 22 which slidably engage grooves formed in the sides of member 18. The cover plate 21 may be secured in position by suitable screws. As clearly shown by Figs. 3 and 4, the top and bottom sides of member 18 are defined by parallel planes, the said sides being embraced by the sides of 110

bolt extension 13 which is adapted to reciprocate thereon.

Loosely placed in channels 18 are the elements by which the combinations are determined. These elements may consist of disks and annuli 23 of the same overall dimensions. Preferably each channel should contain one annulus and four disks in a lock having channels of the length illustrated by the drawings. It is the relative normal positions of the annuli that determines the combination, or key, required to operate the lock. The relative positions of the annuli illustrated by Fig. 4 form a combination corresponding to key 24. Fig. 5 shows this key inserted with the annuli in the several channels brought into vertical alignment. In this position of the annuli, the bolt can be retracted by cam lever 16, as will be obvious from the following description. Formed in member 18 are a plurality of apertures, or holes, 25, which are located in vertical alignment and which intersect channels 19. Projecting from the rear face of bolt 10, and screwed thereinto are a plurality of pins 26, corresponding in number to the apertures 25 and projecting in alignment therewith. It will be obvious that, when a key 24 corresponding to the combination shown in Fig. 4 is inserted to cause all of the annuli to be in alignment with aperture 25, as in Fig. 5, the pins 26 can pass through said apertures and annuli, and, conversely, that when a key which does not correspond to the particular combination is inserted, at least one disk will be opposite an aperture 25, thus preventing retraction of the bolt. It is preferred to provide one or more blind, or idle, sets of disks and annuli, for the purpose of making the solution of the combination more difficult. In these blind sets the annulus is normally in alignment with the respective aperture 25, so that any movement of such a set in the attempt to solve the combination will bring a disk opposite the aperture. Figs. 4 and 5 show two blind sets, viz., the upper and the next to the bottom set.

Latch mechanism operable from the inside of the door is provided to cooperate with the lock above described. The latch illustrated is mounted in a casing 27 secured in a recess in the jamb of the door. It consists of a body portion 28 slidable vertically in casing 27 and formed with upwardly projecting bolt-engaging members 29 and 30. A coil spring 31, bearing at one end against the bottom wall of casing 27 and at its other end against the top of a recess formed in the under side of body 28, yielding holds the latch in its upper or normal position. The upward movement of the latch is stopped by a horizontal plate formed integrally with the face plate of casing 27 and engaging the latch between the

members 29 and 30. The outer face of member 30 has a suitable cam formation, so that the latch will be cammed downwardly by bolt 10 when the door is shut. The door can be opened from the inside by manipulating a knurled head having a shank attached to member 30 and projecting through a vertical slot in casing 27. The door can thus be opened from the inside by any one, but can only be opened from the outside by one provided with a key corresponding to the particular combination for which the lock is set.

Figs. 7 and 8 illustrate a master key adapted for use with a lock constructed as above described. The key here shown consists of a flat body having a number of interior parallel channels 32, in which are slidably mounted pins 33 formed to enter the key openings 20 of member 18. The number of pins will correspond to the number of sets of disks and annuli, or to the number of channels 19 in member 18. Each pin 33 has a number of regularly spaced notches cut in its lower side and adapted to coat with resilient detents 34 attached to the underside of the key body, whereby the pins may be held yieldingly in a number of projected positions. The pins are manipulated by buttons 25 which are attached to shanks secured to the upper sides of the pins and projecting through slots 36 formed in the upper face of the key body. The distance between adjacent notches of the pins corresponds exactly to the diameter of a disk or annulus, so that one knowing the combination of a lock can readily project the pins the proper distances to operate this combination. For instance, if the lock to be operated is set to a combination which requires the disks and annulus in the next to the top channel 19 to be moved through a distance corresponding to three diameters of a disk, and the disks and annulus in the middle channel 19 to be moved two diameters of a disk, the next to the top pin 33 of the master key will be projected until the detent 34 engages the third notch from the notch which it engages in normal position, while the center pin 33 will be projected until the detent engages the second notch from normal position. By normal position of pins 33 is meant the positions in which the ends of the pins when inserted through the reduced openings will just contact the disks resting against the shoulders formed by said reduced openings.

Fig. 9 illustrates a key blank from which a key adapted to operate any combination can be easily formed by one who knows the combination. This blank consists of a simple stamping of brass or other suitable material and can be produced in quantity at a very small price. The blank is formed with a body or handle portion having projecting

therefrom a plurality of pins corresponding to the number of channels 19 and adapted to enter the reduced key openings 20. As indicated by the dotted lines, the pins are 5 cut partly through at regularly spaced intervals, so that a section or sections can be broken off easily, as desired. The length of each of the pin sections exactly equals the diameter of a disk. It will be obvious, therefore, from the foregoing description that a blank of this construction can be quickly formed into a key corresponding to any combination of the lock.

Fig. 10 illustrates still another form of key. This key consists of a body portion having screwed thereinto a number of pins formed to enter the key openings 20. The body has provision for attaching the pins at five different positions thereon, corresponding to the five channels 19. One provided with a key of this construction and having a set of pins adapted to move the sets of disks and annuli through distances corresponding to one, two, three, four etc. 25 diameters of a disk can readily make up a key to suit any combination.

The combination of the lock can be changed very easily. To do this it is only necessary to unscrew the member 18 from the door, withdraw said member, remove the cover plate 21 from the channel openings 19, take out one or more sets of the disks and annuli, and insert or withdraw a disk or disks in front of the annulus or annuli, thus rearranging the relative normal positions of the annuli, which will of course effect a new combination requiring a new key for its operation. The new key can be formed without trouble from the blank 30 shown by Fig. 9 or by substituting new pins in the form of key shown by Fig. 10. A number of blanks or a complete set of pins may be kept on hand for this purpose by the user of the lock, or these articles may be 45 bought as required from the dealer.

Having now particularly described one embodiment of my invention, without, however, intending to limit the scope of the invention to the specific structure disclosed, 50 what I claim as new and desire to secure by Letters Patent of the United States is:—

1. A lock comprising a flat rectangular casing provided with a front cover plate having an opening, a bolt reciprocably mounted in said casing projecting through said opening, said bolt having an open rectangular extension in said casing, a spring between the end of said extension and the end wall of said casing tending to project 55 said bolt, a flat rectangular member extending through said casing at right angles to said bolt and embraced by said rectangular extension, said member projecting on both sides of said casing, said member having formed therein a plurality of superposed

parallel channels having rectangular cross sections with the major axes thereof in the plane of said member, said channels having reduced key-receiving openings at one end of said member and said channels extending 70 upwardly from said reduced openings entirely through said member, a detachable plate secured to the other end of said member covering the openings of said channels, a number of disks and rings loosely mounted 75 in said channels, said member having a transverse aperture intersecting each channel, a plurality of pins fixed to said bolt and projecting in alignment with said apertures, a key having a plurality of pins adapted to 80 be inserted through said reduced openings to cause a ring to be in alignment with each of said apertures, so that said pins can pass through said member, and a manually operable cam acting on the inner end wall of 85 said bolt extension.

2. A lock comprising a casing provided with a front cover plate having an opening, a bolt reciprocably mounted in said casing projecting through said opening, a member 90 extending through said casing at right angles to said bolt and projecting on both sides of said casing, said member having formed therein a plurality of parallel channels having reduced key-receiving openings 95 at one end of said member and extending upwardly from said reduced openings entirely through said member, a detachable plate secured to the other end of said member covering the openings of said channels, a number of disks and annuli loosely mounted in 100 said channels, each channel containing a plurality of disks and one annulus, said member having a plurality of transverse apertures, each channel being intersected by one 105 of said apertures, a plurality of pins fixed to said bolt projecting in alignment with said apertures, a key having a plurality of pins of different lengths adapted to be inserted through said reduced openings to 110 cause an annulus to be in alignment with each of said apertures, whereby the pins on said bolt can pass through said member, and means for operating said bolt.

3. A lock comprising a casing provided 115 with a front cover plate having an opening, a bolt reciprocably mounted in said casing projecting through said opening, a member extending through said casing at an angle to said bolt, said member having formed 120 therein a plurality of parallel channels having reduced key-receiving openings at one end of said member and extending upwardly from said openings entirely through said member, a detachable plate secured to the 125 other end of said member covering the openings of said channels, said member having a plurality of transverse apertures, each channel being intersected by one of said apertures, a plurality of pins secured to said 130

bolt projecting in alignment with said apertures, a number of separate bodies freely movable in said channels, some of said bodies being solid and others formed to permit the passage of a pin on said bolt, a key having a plurality of pins of different lengths adapted to be inserted through said reduced openings to cause one of said last mentioned bodies to be in alignment with each of said apertures, and means for operating said bolt.

4. A lock comprising a casing provided with a front cover plate having an opening therein, a bolt reciprocably mounted in said casing projecting through said opening, a member extending through said casing at an angle to said bolt, said member having formed therein a plurality of channels having reduced key-receiving openings at one end of said member and extending upwardly from said openings entirely through said member, removable means for closing the unreduced openings of said channels, said member having a plurality of transverse apertures, each channel being intersected by one of said apertures, a plurality of pins secured to said bolt projecting in alignment with said apertures, a number of separate bodies freely movable in said channels, there being one body in each channel formed to permit the passage of a pin on said bolt, a key having a plurality of pins of different lengths adapted to be inserted through said reduced openings to cause one of said last mentioned bodies to be in alignment with each aperture, and means for operating said bolt.

5. A lock comprising a casing provided with a front cover plate having an opening therein, a bolt reciprocably mounted in said casing projecting through said opening, a member extending through said casing at an angle to said bolt, said member having formed therein a plurality of channels having reduced key-receiving openings at one end of said member and said channels extending upwardly from said openings, a plurality of pins secured to said bolt, said member having transverse holes in alignment with said pins and communicating with said channels, a number of separate bodies freely movable in said channels, there being one body in each channel formed to permit the passage of a pin on said bolt, a key having a plurality of pins of different lengths adapted to be inserted through said reduced openings to cause one of said last mentioned bodies to be in alignment with each aperture, and means for operating said bolt.

6. A lock comprising a casing, a bolt reciprocably mounted in said casing, a member extending through said casing at an angle to said bolt, said member having

formed therein a plurality of channels having reduced key receiving openings at one end of said member and said channels extending upwardly from said openings entirely through said member, removable means for closing the unreduced openings of said channels, said member having a plurality of transverse holes communicating with said channels, a plurality of pins secured to said bolt projecting in alignment with said holes, a number of separate bodies freely movable in said channels, said bodies being of the same overall dimensions and one of said bodies in each channel being formed to permit the passage of a pin on said bolt, a key having a plurality of pins of different lengths adapted to be inserted through said reduced openings to cause one of said last mentioned bodies to be in alignment with each aperture, and means for operating said bolt.

7. A lock comprising a casing having a front cover plate with an opening, a bolt mounted in said casing adapted to be projected through said opening, a member extending through said casing at an angle to said bolt, said member having formed therein a plurality of longitudinal channels having reduced key receiving openings at one end of said member, said channels extending upwardly from said openings, a plurality of pins secured to said bolt, said member having transverse holes communicating with said channels adapted to receive said pins, a number of separate bodies freely movable in said channels, one of said bodies in each channel being formed to permit the passage of a pin on said bolt, a key having a plurality of pins of different lengths adapted to be inserted through said reduced openings to cause one of said last mentioned bodies to be opposite each of said holes, and means for operating said bolt.

8. In a lock of the kind described, the combination with a bolt of controlling mechanism therefor comprising a member extending transversely to said bolt and adapted to project from the sides of the closure to which the lock is applied, said member having formed therein a plurality of longitudinal channels having reduced openings at one end of said member and extending upwardly therefrom completely through said member, removable means for closing the openings of said channels at the other end of said member, said member having a plurality of transverse apertures intersecting said channels, a number of disks and annuli in said channels, each of said channels having at least one disk and one annulus, a key having a plurality of pins of different lengths adapted to be inserted through said reduced openings to cause an annulus to be opposite each of said trans-

verse apertures, said bolt having a plurality of pins adapted to pass through said apertures and annuli.

9. In a lock of the kind described, the combination with a bolt of controlling mechanism therefor comprising a member extending transversely to said bolt and having formed therein a plurality of longitudinal channels having reduced openings at one end of said member and extending upwardly therefrom completely through said member, removable means for closing the openings of said channels at the other end of said member, said member having a plurality of transverse holes intersecting said channels, a plurality of disks and at least one annulus in each channel, said bolt having a plurality of pins adapted to pass through said holes and annuli.
10. In a lock of the kind described, the combination with the bolt of controlling mechanism therefor comprising a member extending transversely to said bolt and having formed therein a plurality of longitudinal channels having reduced openings at one end of said member and extending upwardly therefrom completely through said

member, removable means for closing the openings of said channels at the other end of said member, said member having a plurality of holes intersecting said channels, a plurality of disks and at least one annulus freely movable in each channel, all of said disks and annuli being of the same overall dimensions, said bolt having a plurality of pins adapted to pass through said holes and annuli.

11. In a lock of the kind described, the combination with the bolt of controlling mechanism therefor comprising a member extending transversely to said bolt and having formed therein a plurality of longitudinal channels having reduced key-receiving openings at one end of said member, said member having a plurality of transverse holes intersecting said channels, a plurality of disks and annuli in said channels, said bolt having a plurality of pins adapted to pass through said holes and annuli.

In testimony whereof I hereunto affix my signature.

EDWARD R. VIVES.
